TO BLAISDELL MACHINERY CO., OF BRADFORD, PENNSYLVANIA, A CORPORATION
OF PENNSYLVANIA.

OPERATING MEANS FOR COMPRESSOR-VALVES.

1,209,077.

Specification of Letters Patent. Patented Dec. 19, 1916.

Application filed March 2, 1915. Serial No. 11,485.

To all whom it may concern:

Be it known that we, FRANK M. TITUS and DELMER B. SCHWAB, citizens of the United States, residing at Bradford, in the county of McKean and State of Pennsylvania, have invented certain new and useful Improvements in Operating Means for Compressor-Valves, of which the following is a specification.

10 Our invention relates to improvements in air compressors, and is directed more to the operation and control of a Corliss valve on a single acting, direct driven gas engine air compressor cylinder.

15 The primary object of our invention is to provide an actuating means for the movement of the valve, whereby the valve may be maintained in an open position, to relieve the compressor cylinder of its compression load, until the direct connected gas engine, actuating the compressor, has reached its maximum efficiency or approximately full speed.

20 Other objects of our invention are to provide a positive cam operated valve opening movement, with a spring actuated, cam timing, valve closing movement, the advantages of which will readily appear to those skilled in the art.

25 A further object of our invention is to provide actuating means to the valve movement whereby it may be so timed that the valve is opened to the admission of fluid into the compressor cylinder, at a time when the pressure on each side of the valve is approximately the same, thereby reducing wear upon the valve, and strains upon its operating mechanism.

30 It is well known in the art that the general application of valves to compressor machines is beset with many difficulties and that mechanically operated valves, especially where eccentrics are employed to perform the opening and closing movement, are customarily slow and deliberate, as well as non-intermittent and sluggish, and otherwise unadapted to meet the requirements of the rapid and speed varying motions required at the end of the piston stroke, to properly provide for the passage of incoming air at the correct point of the piston movement in the beginning of the suction stroke.

In our improved valve operating mecha-

nism we dispense with the use of the common form of eccentric movement, and substitute therefor a cam operated valve actuating means, by which the valve is adapted to remain full open for a longer period while air is being admitted to the cylinder and furthermore does not rotate as far, as when operated by the usual eccentric.

A further object of this invention is to provide a compressor with the foregoing capabilities and which in addition thereto, is capable of being run at a speed higher than is practical with other forms of valves.

In a compressor of this type where the piston receives its movement from a crank and a connecting rod, there is a period during which the piston passes through the zero point of reciprocatory motion, or dead center, and wherein the piston has but slight movement. In our invention we take advantage of the uniform revoluble movement of the crank shaft, and at the beginning of the suction stroke movement of the piston, and before the piston has acquired to any great extent its reciprocatory velocity, we employ means to transfer the movement of the crank shaft into rapid speed varying, intermittent and effective motion to a controlled valve, through a suitable cam, to perform the rapid opening of the intake movement of the valve, and to apply a guiding and timing control to the spring actuated closing movement.

There are various other advantages incident to the construction shown, and these will appear from the description to be given in connection with the accompanying drawings, illustrating one embodiment of our invention, which however, is susceptible of modification in various respects.

Figure 1, is a side elevation of a compressor, as seen from the cam end, with the valve actuating mechanism applied thereto. Fig. 2, is an enlarged detailed view of the actuating mechanism, with a part of the connecting rod broken away. Fig. 3, is an enlarged detailed view similar to Fig. 2, showing the valve held in an open position. Fig. 4, is a diagrammatic view, showing the compressor cycle by three positions of full functional operations (numbered I, II, III), I, at the end of the discharging air, II, taking free air, III, compressing air.

Referring to the drawings more particularly to Fig. 1, it will be seen that the compressor illustrated which is the one selected for the purpose of illustrating the use of our invention, is of the single acting direct driven type, wherein it is directly connected to a gas engine (not shown) having a crank shaft in common to both the gas engine and the compressor. Direct connected engine driven compressors, are well known in the art, and as the motive power is not a part of this invention, no further description thereof is deemed necessary.

1, is the base to which is suitably attached 15 at the one end, the cylinder 2, and mounted upon the other end is the rotating crank shaft 3. Located upon the crank shaft 3, is a valve movement actuating cam 4, securely keyed against rotative movement on 20 the crank shaft 3, by the key 5. Suitably mounted on the side of the base 1, and projecting outwardly in parallel relation to the crank shaft 3, is a stud 6. Mounted on the stud 6, and adapted for oscillating movement thereon is a valve rod crank 7, having 25 three projecting arms A, B and C.

Located on the upper arm B, of the valve rod crank 7, is a roller 8, mounted on the stud 9, which projects horizontally from the 30 crank 7. The roller 8, is adapted for rotative movement, and to revolve in its contact with the face of the cam 4. The shaft 3, in its revolving motion, causes the cam 4, to engage the roller 8, and in turn to impart oscillating movement to the valve rod crank 7.

To provide for normally maintaining the roller 8, in operative contact with the cam 4, there is pivotally connected to the arm C, 40 a rod 10, whose lower end passes through the guide lug 11, which is attached to the base 1, by the bolts 12—12'. Located near the upper end of the rod 10, is a fixed shoulder 13, encircling the rod 10. Between the 45 fixed shoulder 13, and the guide lug 11, is a compressible coil spring 14, adapted to be compressed in the oscillating movement of the crank member 7, and to normally exert a contact pressure between the roller 8, and 50 the face of the cam 4.

Located on the projecting arm A, of the crank member 7, is a projecting stud 15. Mounted on the stud 15, and adapted for rotating movement thereon, is a valve rod 55 journal 16. Attached by suitable means to the journal 16, is the valve rod 17. Attached by suitable means at the opposite end of the valve rod 17, is the journal 18. Located within the journal 18 and adapted for 60 rotative movement therein is the wrist pin 19, projecting horizontally from the valve crank 20. The valve crank 20 is mounted upon the valve stem 21, and held against rotative movement thereon by the constricting bolts 22. The valve stem 21 is connect-

ed in any suitable way to a valve gudgeon 21', (Fig. 4) having a cavity on the one face, similar to that of an ordinary Corliss valve. Formed integral with the valve crank 20, and located substantially opposite to the 70 wrist pin 19, is a projecting lug 23, the purposes of which will be hereinafter more fully explained.

Projecting outwardly above the valve stem 21, and in parallel relation thereto is the 75 stud 24. Mounted upon the stud 24, and adapted for rotative movement thereon, is a lever 25, having at the one end a handle 26, and at the opposite end an extended lug 27. Located for normal contact with the lug 27, 80 when the lever 25, is in the position shown in Fig. 2, is a projecting stud 28, adapted to hold the lever 25, in the position shown.

In the rotation of the shaft 3, as the elevated portion of the cam 4, comes in contact with the roller 8, there will be an oscillating movement imparted to the crank member 7, which will cause a downward movement to the spring rod 10, thereby compressing the coil spring 14, between the shoulder 13 and the projecting lug 11. This state of compression of the spring 14, will exist as long as the high surface of the cam 4, is in contact with the roller 8. As the roller passes from the high surface and descends 85 to the lower surface of the cam 4, the compression of the spring 14, will exert itself and move the roller 8, nearer the center of the shaft 3, in which position it will remain until the high surface of the cam 4, again 90 engages the roller 8, when a corresponding movement of the crank member 7, will again be instituted.

As the crank member 7, is oscillated, a reciprocating movement is imparted to the 105 valve rod 17, which conveys rotative movement to the valve crank 20, which in turn rotates the valve gudgeon 21' attached to the valve stem 21, and provides for the opening and closing of the air port communicating 110 with the interior of the cylinder 2.

As previously referred to, one of the objects of this invention is to provide means whereby the valve may be maintained in an open position to relieve compression within the compressor cylinder when so desired. This is accomplished by moving the handle 115 26 of the lever 25, from the position shown in Fig. 2, to the right as shown in Fig. 3, until it bears against the stud 28. This movement of the lever 25, is accomplished during the period of full opening of the valve, when the lug 23, has reached the farthest point in its travel away from the stud 24. With the lever 25, in the position shown in Fig. 3, as the valve crank 20, is about to begin its backward or closing rotation, the projection 27, intercepts the rotative movement of the crank 20, by its engagement with the lug 23, and the valve is 120 125 130

maintained in an open position as long as the lever 25 remains in the position shown in Fig. 3.

With the valve movement arrested as shown in Fig. 3, the crank shaft 3, is free to rotate without any appreciable movement being conveyed in such rotation, to the crank member 7, and the compressor actuating mechanism is free to operate with the valve remaining in an open position to the relief of the compression load, thereby facilitating easy starting of the compressor actuating means, and permitting the establishment of the highest rotative movement thereof, before the compressor valve is thrown into operative movement, which is accomplished by throwing the lever 25, from the position shown in Fig. 3, to the position shown in Fig. 2.

In the application of our novel valve actuating means we provide a construction whereby the spring actuated valve closing means will operate to close the valve under all normal condition. We also provide an element of safety to the valve structure and its component parts against breakage, when through failure of proper lubrication, or the location of foreign matter in the valve seat, the valve becomes obstructed against closing, the valve will remain in an open position avoiding injury to the valve mechanism, by its being automatically thrown out of operative connection with the crank shaft of the compressor, thus providing a safety which it is impossible to obtain with the positively controlled eccentric driven Corliss valves.

Our invention pertains primarily to the valve actuating means shown, and to the relative position of the piston to the movement of the valve actuating means. The discharge of the compressed fluid from the compressor cylinder may be taken care of in any of the ways well known in the art and such details, not being a part of this invention, further description of the details thereof are not necessary. The timing of the valve actuating means in relation to the piston travel, forms however an important feature of this invention.

In the diagrammatic view I, shown in Fig. 4, it will be observed that the crank shaft having been turned in its operative direction, counter clockwise, that the crank pin 31 has passed the dead center and the piston has already begun to move in the direction of the suction stroke. Previous to such movement, there has been a discharge of the compressed fluid from the cylinder 2, such discharge ceased at the commencement of the movement of the piston toward the suction stroke. There still remains however within the clearance space 34, between the piston and the cylinder head, a residue of compressed fluid. This fluid in its compressed state has a greater static pressure

than that of atmospheric air, and there is therefore a higher pressure exerted on the face of the valve gudgeon 21', closing the cylinder port 32, than the atmospheric pressure at the port 33.

Referring again to diagram I, it will be observed that the gudgeon valve 21' has not yet opened to the admission of atmospheric air, although the crank shaft 3, has passed the dead center by several degrees, and the piston has commenced to move in the direction of the suction stroke. In such movement the piston begins to increase the clearance space 34, and to thereby progressively reduce the static pressure within the clearance space, until the pressure therein is reduced materially toward atmospheric, or until the pressure on the faces of the valve gudgeon at the respective parts, bears sufficiently near equal, to make the rotative movement of the valve gudgeon easy and without undue friction. When such point has been reached the valve gudgeon is adapted to open for the admission of air into the cylinder at the suction stroke as is shown in diagram II. Under this novel arrangement there is no movement of the valve gudgeon, while there is any perceptible pressure thereon.

The operation of our improved valve actuating mechanism will be readily apparent to those skilled in the art. The revolving movement of the cam 4, imparts oscillating movement to the crank 7, which in turn reciprocates the valve rod 17, conveying rotary movement to the valve crank 20. With the lever 25, resting in the position shown in Fig. 2, the valve crank 20, is free to oscillate in its operative function to open and close the valve port. By placing the lever 25, in the position shown, in Fig. 3, at a period when the valve crank 20 is in its farthermost position of opening, the oscillating movement of the valve crank 20, will be arrested by its contact with the extension lug 27, of the lever 25, and will remain in such open position as long as the lever 25, is in the position shown in Fig. 3, due to the valve closing means being held inoperative as shown. When it is desired to again place the valve actuating means in operation the lever 25, is changed from the position shown in Fig. 3, to that of the position shown in Fig. 2, which allows the free rotation of the valve crank 20. With the valve held in the open position, the compressor piston is free to reciprocate without creating a compression load, and the compressor actuating means may be more easily started, and may be accelerated up to its maximum speed and power, before placing the fluid compressing means in operation. When this state of accelerated speed of the compressor actuating means has been reached the compressor may be put under load by throwing the lever 25,

from the position shown in Fig. 3, to the position shown in Fig. 2, which allows the free rotation of the valve crank 20.

While in accordance with the provisions 5 of the statutes we have herein described and illustrated the best form of the invention now known to us, it will be apparent to those skilled in the art that changes may be made in the form of the apparatus disclosed without departing from the spirit of our invention, and that certain features of the invention may be advantageously employed in some circumstances without a corresponding use of other features, and we do not wish 10 to depart from the spirit of our invention, and that certain features of the invention may be advantageously employed in some circumstances without a corresponding use of other features, and we do not wish 15 the claims hereinafter made to be limited to the particular form of the apparatus disclosed more than is made necessary by the state of the art.

Having now described our invention, what 20 we claim as new and desire to secure by Letters Patent, is:

1. In an air compressor the combination of an inlet valve having oscillating movement adapted to control the admission of air, 25 actuating means to operate said compressor comprising a reciprocating valve rod, cam connections with said operating means fashioned to permit the oscillating valve to remain stationary in the successive positions 30 required for the pumping operation, and to quickly change its position to give intermittent motion to the valve during each revolution of the actuating means, with independent means to maintain the oscillating valve 35 stationary over more than one revolution of said reciprocating rod actuating means.

2. A compressor valve actuating device comprising a rotating cam, an inlet valve having oscillating movement, a reciprocating 40 valve rod, actuating means having a direct connected engagement with said cam, fashioned to permit the oscillating valve to remain stationary in successive positions, and independent means for maintaining the valve 45 rod stationary over more than one revolution of said rod actuating means.

3. In a direct connected gas engine air compressor having a compressing cylinder, a port connected with said cylinder, a compressing piston working in said cylinder, a crank shaft actuating said piston, and an irregular faced cam on said crank shaft, the combination with an oscillating valve controlling said port, of means comprising a 50 reciprocating valve rod operated by said cam, for actuating said valve in fixed time relation to the movement of the compression piston, whereby the pressure on opposite faces of the valve is substantially equal and 55 independent means for maintaining the valve rod stationary over more than one revolution of said rod actuating means.

4. In a direct connected gas engine air compressor, having a cylinder, a port connected with said cylinder, a compressing pis-

ton working in said cylinder, and a crank shaft actuating said piston, the combination with an oscillating valve controlling said port, of means for opening said valve comprising a reciprocating valve rod actuating member, a cam on said crank shaft adapted to convey reciprocating movement to said valve rod actuating member to open said valve, and a retracted spring bearing on said valve rod actuating member adapted 70 to close said valve in fixed time relation to the movement of the compression piston and independent means for maintaining the valve rod stationary over more than one revolution 75 of said rod actuating means.

5. In a direct connected gas engine driven air compressor, having a compressing cylinder, a port connected with said cylinder, a compressing piston working in said cylinder, a crank shaft actuating said piston having a cam thereon, the combination with an oscillating valve controlling said port, of a reciprocating rod between said crank shaft and the oscillating valve, adapted to receive intermittent reciprocating motion from said 85 cam whereby the intermittent movement of the oscillating valve will have a proportion of movement less than the proportion of rest.

6. In an air-compressor, the combination of an oscillating valve adapted to control the admission of air into said compressor, power connections to operate the compressor and cam connections therewith fashioned to permit the valve to remain stationary in the successive positions required for the pumping 90 operation and to quickly change its position to give intermittent motion to the valve, with means for imparting to said oscillating valve a proportion of movement less than the proportion of rest.

7. An apparatus of the character described, comprising an irregular outlined cam operatively mounted for rotative movement, a reciprocating valve rod actuating lever placed in operative contact with said cam, a valve 100 crank adapted for an oscillating movement, a crank pin projecting horizontally from one end of said valve crank, a projecting lobe on the opposite end of said valve crank, a horizontally projecting stud located near the rotative path of said lobe, and a lever mounted on said stud and adapted to be moved into the path of said lobe to arrest the rotative movement substantially as described.

8. An apparatus of the character described, 110 comprising an irregular outlined cam operatively mounted for rotative movement, a horizontally projecting stud adjacent to the path of said cam, an oscillating lever mounted on said stud adapted to receive movement 115 from said cam through a roller contact at the upper end and having a horizontally projecting stud rigidly attached to the lower end, a valve rod terminal mounted on said stud, an oscillating valve crank, a valve ac- 120

tuating rod adapted for reciprocating movement connected to said terminal at the one end with valve crank operating terminal at the other end, a projecting lobe on one end 5 of said valve crank, a horizontally projecting stud located near the rotative path of said lobe and a lever mounted on said stud and adapted to be moved into the path of said lobe to arrest the rotative movement 10 substantially as described.

9. In an air compressor, the combination with an oscillating valve adapted to control the admission of air into said compressor, power connections to operate said compressor, 15 valve actuating cam connections therewith, whose periphery is divided into high and low surfaces in radial relation to a common center, of valve oscillating means yieldingly held against said cam adapted to receive reciprocating movement through contact with the periphery portion of said cam interposed between the high and low surfaces, and independent means for holding 20 said valve oscillating means stationary over 25 more than one revolution of said cam.

10. In combination with a valve actuating cam of an air compressor, whose periphery is divided into alternate high and low surfaces in radial relation to a common center, 30 having an abrupt deviation of its radial curve interposed therein, of valve oscillating means yieldingly held against said cam receiving reciprocating movement through contact with said abrupt portions and remaining 35 inactive during the rotation of the cam through the arcs of said radial curve, with

independent means for maintaining said valve oscillating means stationary over more than one revolution of said cam.

11. In combination with a valve actuating 40 cam of an air compressor, whose periphery is divided into alternate high and low surfaces in radial relation to a common center, having an abrupt deviation of its radial curve interposed therein, of valve oscillating 45 means yieldingly held against said cam adapted to receive reciprocating movement from said abrupt deviation, and to remain inactive during the rotation of the cam through the arcs of said radial curve, and independent means for maintaining said valve oscillating means stationary over more than one revolution of said cam.

12. In combination with a valve actuating 50 rotating cam of an air compressor, whose periphery is divided into alternate high and low surfaces, in radial relation to a common center, of valve oscillating means spring actuatingly held against said cam, adapted to be cam actuated in one direction, and spring 55 actuated in the opposite direction, with independent means for placing the valve oscillating means in and out of cam engagement while said cam continues to rotate.

In testimony whereof we have affixed our 60 signatures in presence of two witnesses.
